RULER

Charles H. Little, Cleveland Heights, Ohio

Application April 1, 1931, Serial No. 526,913

8 Claims. (Cl. 33—107)

This invention relates to rulers and has especial reference to rulers employed with protractors such as form a part of drafting machines. More particularly the invention relates to improvements in the chucking facilities heretofore applied to rulers to enable them to be chucked in the chuck arms of protractors.

The principal object of the present invention is to provide improved chucking or holding of parts, and which permit chucking below the top surface of the ruler so as to make the rulers more convenient for use and cause them to have an improved appearance.

When wooden or other rulers are chucked in a protractor such as forms a part of a drafting machine, it has been customary to chuck the ruler at its top surface, this being usually done by securing to the top of the ruler a chuck plate which extends for some distance from the end 20 along the top of the ruler. In order that the ruler may be reversed, these chuck plates are provided at both ends of the ruler, and these, of course, add to the weight of the ruler, and, as the chuck plates are located on top of it, they 25 interfere somewhat with the use of the ruler, particularly when the rulers are in the form of scales, and they detract from the appearance of the article.

All these disadvantages are overcome and the 30 advantages or objects stated above are attained very effectively by the present invention, which may be here briefly summarized as consisting in certain novel details and combinations which will be described in the specification and set forth 35 in the appended claims.

In the accompanying sheets of drawings which show the preferred embodiment of the invention,

Figure 1 is a top plan view of the ruler with 40 portions broken away, this ruler being in the form of a scale;

Fig. 2 is a bottom view of the same;

Fig. 3 is a cross-sectional view of the same on an enlarged scale;

Fig. 4 is a similar view of the scale, the section being taken through one of the chucks of the scale and through the chuck arm; and

Fig. 5 is a plan view of a protractor with two rulers, portions only of which are shown, held 50 on the chuck arms at right angles to each other.

Referring to the drawings, the ruler shown therein includes a metal stiffening core 10 and a suitable non-metallic covering 11, such as cel luloid or pyralin, which encloses the core and is 55 of course tightly fitted thereon. The core 10 is

preferably formed by extruding and drawing processes from a suitable light but stiff metal, such as duralumin or magnesium alloys. In the preferred way of producing the core, a strip having the approximate cross-sectional shape of the core and of suitable length is extruded and is then passed through drawing dies in which the desired cross-section is obtained. It is then placed in a stretching machine to straighten it as much as possible, and after cores of proper 10 lengths for use in the rulers have been cut from the strip, the cores are subjected to a further straightening operation by subjecting them to severe pressure in a press between dies which are shaped in conformity with the shape of the 15 core.

The covering is preferably applied by heat and pressure in a mold, as described in my United States Patent No. 1,728,420, the covering of course, enclosing the core, including the top and 20 bottom surfaces and the ends, although certain portions of the covering on the center line of the top are later removed to accommodate the heads of screws which hold the chucks to the under channelled surface of the ruler. The rulers 25 may be in the form of scales or straight edges, but if in the form of scales, the top will usually be beveled along both sides and the beveled surfaces will be provided with the usual graduations and characters. If the ruler is in the form of 30 a straight edge, the bevels will usually be omitted from the top surface of the ruler.

According to the provisions of the present invention the ruler is provided on its lower side and extending centrally from end to end with 35 a channel which I prefer to be somewhat greater than one-half the width of the ruler and that its cross-section be approximately one-third of the cross-sectional area of the ruler. The top wall of the channel is, of course, parallel to the 40 top of the ruler and its side walls are slightly tapered.

This channel has numerous functions, and has utility both in the production of the core and the ruler as a whole and in subsequent use, particularly when chucked in protractors such as form a part of the drafting machines. Perhaps its greatest utility lies in the fact that it admits of a greatly improved method of and means for chucking the ruler, but this will be referred to 50 presently. Among the other advantages utilized in the manufacture of the ruler and in its use independently of protractors and the chuck arms thereof might be mentioned the following. The channelled section of the core increases greatly 55

the stiffness of the core and thus enables me to use a stiffer metal without increasing the weight, or, as otherwise stated, as compared with a core such as shown in my prior patent, it will have considerably less weight if metal of the same kind is employed.

The channel is useful in producing the core itself for it enables me to produce cores free of twists and bends which was not always the case with the unchanneled cores. Heretofore I experienced considerable difficulty in obtaining cores which were truly straight. In producing a quantity of cores, a portion of them would be straight when produced by the methods described above, but others would not be so, but when I produce these channeled cores by first extruding the strip, passing it through a drawing die, stretching the strip, and then after the strip is cut into core lengths subjecting them to pressure between dies in a press, the cores are uniformly straight to an extremely high degree of accuracy. This result is obtained because by utilizing straightening dies, the lower one of which is provided with a part which conforms to the shape of the channel and of course extends for its full length, the upper die of the press, when it strikes the core which is easily correctly placed and held on the lower die with said part filling the channel, removes the last vestige of any twisting or bending distortion, with the result that the cores are produced uniformly straight.

Finally, it performs a very useful function in that part of the process of forming the rulers wherein the non-metallic covering is molded by heat and pressure around the core. In this connection it might be stated that previous to the conception of the channeled core difficulty was encountered by me in keeping the core central and in keeping it from bending when subjected to the enormous pressure necessary in molding the one-piece unitary covering around the core. In producing a quantity of rulers, the cores of some of them would be properly positioned but not so of others. I found that in some instances the cores had a tendency to float, so to speak, in the celluloid so that they would not be centrally positioned therein. To overcome this, I attempted to hold the core in position by spaced pins engaged in openings of the core, but this expedient would not suffice in some instances for the pressure of the celluloid on the core seemed to bend it. These difficulties are entirely overcome by the channeled core for I find that in molding the non-metallic plastic material around the core with a rib on the lower mold member extending for the full length into the channel, the shifting of the core in the mold and the bending of the core are eliminated so that in the production of a quantity of these rulers they are substantially uniform in the desired centralized relationship of the core in the celluloid or other covering material.

A greater advantage of the channeled rulers lies in the fact that by reason of the channel I am enabled to chuck the ruler on the chuck holding arm of a protractor with the chucking below the top surface of the ruler, in fact on the under side thereof. For the accomplishment of this I provide on the under side of the ruler and against the upper wall of the channel a plurality of independent chucks which are adapted to engage and interlock with the chuck arm which is extended into the channel and forms substantially to the cross-sectional shape

thereof, the chucks being so formed that they will engage in suitably formed slots in the chuck arms. The form and location and the manner of securing the chucks in the channel are well illustrated in Figs. 2, 3, 4, and 5, wherein the chucks are designated by the reference character 13. The number of chucks which are provided for each end of the ruler will generally depend upon the length of the latter. I prefer to employ two or more for each end of the ruler. I find that for a twelve inch ruler two chucks are ample, but for longer rulers, such as eighteen inch, I prefer to employ three chucks at each end, these chucks being equally spaced. Each chuck is formed from a piece of metal slightly elongated in form with flat sides 13^a (Fig. 2) which extend longitudinally of the ruler and are slightly tapered, being slightly convergent toward the adjacent end of the ruler, i. e., toward the protractor in which they are to be chucked. Likewise, the walls forming the flat sides are slightly tapered toward the top of the channel, as shown at 13^b in Fig. 3. Each chuck is held in place against the upper wall of the channel and centrally of the latter by a small screw 14 through an opening in the ruler, which opening is somewhat larger than the shank of the screw so that the screw, and therefore the chuck, may be adjusted in any direction. The head 14^a of the screw, which is preferably flat and circular and of a thickness only very slightly, if any, greater than the thickness of the covering on the core, bears against the core, as clearly shown in Fig. 4, the covering being cut away so as to provide clearance for the head. Obviously, when the screw is tightened, the chuck is drawn up tightly against the upper wall of the channel, and prior to tightening it, the chuck can be given the desired positioning so that it will properly fit the slot in the chuck arm. This method of chucking is especially well adapted for quantity production.

In Fig. 5 I have shown how the chucking is accomplished. I have here shown rather conventionally a protractor which forms the subject matter of a companion application Serial No. 526,912 filed of even date herewith. It will be sufficient to state that this protractor includes a protractor plate 16 which is pivoted to the center of and is rotatable with respect to a notched holding plate 17. The protractor includes also a chuck arm plate 18 having two chuck arms 19 and 20 to which the rulers are adapted to be chucked, these arms being as usual at right angles to each other. A protractor of this kind is generally secured to the parallel motion mechanism of a drafting machine, the notched plate 17 having extensions 17^a by which this may be brought about. Additionally, the protractor has a centrally located handle 21 which is grasped by the operator when the protractor plate and rulers are to be turned, and there is supported in this instance by the chuck arm plate 18 a ratchet pawl 21^a the nose of which is adapted to snap into the notches of the notched plate 17 to position the protractor when it is turned and to hold it in the commonly used angles, the pawl being released from the notched plate by a suitable thumb-piece 22.

As before stated, the chuck arms 19 and 20 are at right angles to each other and one is longer than the other so as to accommodate rulers of different lengths. These chuck arms in cross-section conform to the cross-section of the channel and they are adapted to extend into the 75

channels of the rulers when the latter are chucked thereto. The thickness of the chuck arms is about the same or slightly less than the depth of the channels, as indicated in Fig. 4.

- 5 Each of these chuck arms has a plurality of slots 23 which extend transversely through the chuck arms centrally thereof, which slots are adapted to receive the chucks 13 of the corresponding ruler. The number of these slots will depend upon the number of chucks with which the ruler is provided. That is to say, for a ruler having two chucks at each end, the chuck arm will have two of these slots, as shown in the shorter chuck arm 19. If the ruler has three or more chucks 15 at each end, the chuck arm will have a corresponding number of equally spaced slots, as provided in the chuck arm 20 which is shown as having three slots adapted to receive three chucks. These slots have tapered sides, the narrower ends of the slots being preferably toward the protractor and the side walls of the slots are undercut, as indicated in Fig. 4. The relatively large ends of the slots are wide enough so that the chucks will slip into the slots, and in chucking 25 the ruler it is placed over the chuck arm with the channel receiving the chuck arm and with the chucks in the larger end of the slots, and then the ruler is slid in this instance toward the protractor, whereupon the chucks will engage 30 tightly the side walls of the slots and the chuck arm will be pulled up against the bottom of the channel, as in Fig. 4. To release the ruler, it is merely necessary to slide it outwardly and then lift the ruler off the chuck arm.

35 Thus, with the chucking means herein shown, the top of the ruler is clear and not obstructed as heretofore by a chuck plate and by a chuck arm extending for a distance over the ruler. This adds to the convenience in using the drawing instrument and improves its appearance, the ruler for its full length being unobstructed by parts which heretofore have extended over a portion of its length.

The use of two independent chucks instead of 45 one has several advantages. Two small chucks, such as herein illustrated, spaced apart as shown have less weight than the single long chuck heretofore necessary. Additionally, the two chucks provide four bearing surfaces on the chuck arm 50 instead of three as heretofore. In consequence, there is a better holding action which reduces materially the flexibility of the ruler and therefore adds to the accuracy of the instrument as a whole. Either or both of the two chucks (or 55 three if three are employed) can be independently adjusted so that perfect alignment can be obtained and to bring about equal bearing action of both sides of the chuck on the chuck arm, it being understood that the chucks have the necessary lengthwise and crosswise adjustment to attain these ends. Finally, it might be stated that a plurality of chucks formed and spaced apart as illustrated and described do not have the disadvantage of a single relatively long chuck in 60 that the latter at times would bend and had a certain amount of springiness, all of which had the tendency to effect the alignment of the ruler and to increase its lateral flexibility to the detriment of accuracy.

70 From the above it will be seen that the cross-sectional shape of the composite ruler has advantages independent of those which flow from the new chucking features. It will be seen also from the above that the use of two or more 75 separate chucks at each end of the ruler in-

stead of a single long chuck has advantages regardless of whether the chucking is done on the under side of the ruler or on the top. The arrangement of the separate chucks in the channel and the method of chucking herein described are 5 preferred, but I regard it within the scope of my invention to use chucks similar to those described but mounted on the top surface of the ruler with the heads of the screws in the channel, in which event the chuck arm will extend 10 over the ruler and engage the chucks as before.

It will be seen from the above that my improved channelled ruler either in the form of a scale or a straight edge has numerous advantages in permitting an increase in the stiffness and a reduction in weight, and facilitates the manufacture of composite rulers having a metal core and a covering of celluloid or the like, and, together with the chucks preferably secured in the channel, permit a greatly improved method of chucking with numerous attendant advantages over the method or methods heretofore employed.

While chucking in the channel of the lower side of the ruler, as herein explained, is highly desirable, nevertheless I do not desire to be confined to that method of chucking. For example, the channelled ruler and the use of two or more separately and independently adjustable chucks at each end of the ruler are important whether bottom chucking or top chucking is employed. Of course, if top chucking is utilized, the chucks will be secured on the top side of the ruler with the heads of the screws engaging the top wall of the channel and the chuck arms would extend over the ruler and engage the chucks as 35 before, but, of course, with that arrangement only part of the herein-mentioned advantages would be attained as compared with the preferred construction, and therefore the preferred method of chucking herein described and illustrated.

While I have shown the preferred construction, I do not desire to be confined to the precise details as changes may be made without departing from the spirit and scope of the invention, 45 and I therefore aim in my claims to cover all such modifications.

Having thus described my invention, I claim:

1. A ruler adapted to be connected to a ruler supporting arm of a drafting machine, said ruler 50 having a channel in one side thereof to receive the ruler supporting arm, and a chuck secured in said channel for chucking said ruler to the ruler supporting arm.

2. A ruler adapted to be chucked to a ruler supporting arm of a drafting machine having a channel on the lower side thereof to receive the ruler supporting arm, and a tapered chuck secured in said channel for chucking the ruler to the ruler supporting arm, means extending from 60 the chuck and exposed at the upper side of the ruler.

3. A ruler adapted to be chucked to a ruler supporting arm of a drafting machine having a channel in one side thereof adapted to receive 65 the ruler supporting arm, and a chuck secured to the ruler for chucking the latter to said supporting arm, said chuck being tapered lengthwise of the ruler and lying wholly within said channel.

4. A ruler adapted to be chucked to a ruler supporting arm of a drafting machine having a plurality of tapered chucks secured thereto at one end thereof for chucking the ruler to said supporting arm, said chucks being independently 75

- secured to and independently adjustable on the ruler.
5. A composite ruler adapted to be chucked to a supporting arm comprising a stiffening core having a channel in one side thereof and a non-metallic covering molded to the core and conforming to the shape of the channel whereby a channel is formed in the side of the composite ruler adapted to receive the supporting arm, and 10 a chuck secured in the channel of the ruler for chucking the ruler to the supporting arm.
6. A ruler adapted to be chucked to a ruler supporting arm of a drafting machine having a channel in one side thereof adapted to receive 15 the ruler supporting arm, and a plurality of tapered chucks secured to the ruler in said chan-
- nel for chucking the ruler to said supporting arm.
7. A ruler comprising a core provided with a channel in the underside thereof, a non-metallic covering enclosing said core and conforming thereto, said channel being adapted to receive a supporting arm, and a plurality of chucks secured in said channel and adapted to engage said supporting arm.
8. A ruler comprising a core, a non-metallic covering enclosing said core, said ruler being provided with a channel on the lower side thereof and an opening extending from the top of the ruler to the channel, a chuck in said channel, and a screw extending through said opening for holding said chuck. 15

CHARLES H. LITTLE.
